UNITED STATES PATENT OFFICE.

WILFRED H. BUTCHER, OF BURWELL, NEBRASKA.

CALCULATOR.

Application filed June 7, 1920. Serial No. 387,007.

To all whom it may concern:

Be it known that I, WILFRED H. BUTCHER, a citizen of the United States, residing at Burwell, in the county of Garfield and State of Nebraska, have invented certain new and useful Improvements in Calculators, of which the following is a specification.

This invention relates to new and useful improvements in calculators, the primary 10 object of the invention being to provide a device capable of adding and subtracting, the invention being particularly adapted for adding a number of purchases and subtracting the amount of the purchases from a 15 given amount to determine the amount of change which the purchaser is to receive.

An important object of the invention is to provide a device of the above nature which includes a pair of movable members 20 and means whereby they may be moved in unison or independently as occasion demands.

Another object of the invention is to provide a calculator including means for mounting a pair of rotatable members whereby they may be rotated in unison or independently, also means for automatically returning the rotatable members to their normal 25 position.

Another object of the invention is to provide a device of the above named character including means for releasably retaining one of the movable members in a set position while the other is being moved to accomplish 30 the desired function.

Other objects and advantages of the invention will become apparent during the course of the following description.

In the accompanying drawings forming a 40 part of the application and wherein like numerals are employed to designate like parts throughout the several figures,

Figure 1 is a front elevation of the calculator, parts thereof being removed.

Figure 2 is a side elevation of the same.

Figure 3 is an enlarged fragmentary section taken through the device, and

Figure 4 is a view illustrating a portion of the engaging faces of the movable member.

Referring to the drawing wherein for the purpose of illustration is shown the preferred embodiment of the invention, the numeral 5 designates a base having mounted 55 thereon a casing 6, the upper forward portion 7 of which is arcuated in the manner

illustrated most clearly in Figure 2 and is provided with a sight opening 8 having pointers 9 extending toward the center of the opening from opposite side edges thereof. A pair of movable members constituting a tally wheel 10 and a count wheel 11, are rotatably mounted in the casing, the count wheel 11 being rotatably mounted upon a shaft 12 extending transversely of the casing, while the tally wheel 10 is keyed thereto.

The end of the shaft 12 adjacent the tally wheel 10 is journaled in a bearing plate 13 secured to one side of the casing. The opposite end of the shaft extends through the count wheel 11 and into a tubular stem 14 for sliding engagement therein. The inner end of the stem is provided with an annular flange 15 which is secured by suitable fastening elements 16 to the hub of the count wheel 11. The outer end of the stem is journaled through the side of the casing and extended a slight distance therebeyond to be equipped with a suitable knob or grip 17 whereby the stem and its associated count wheel may be reciprocated upon the shaft 12.

In order to automatically return the count wheel to its normal position and to disengage it from its coacting tally wheel 10, a coiled spring 18 encircles the tubular stem 14, and one end of the spring is secured to the count wheel while the opposite end thereof is fastened to the casing. A similar coiled spring 19 encircles the shaft 12 and has one end secured to the tally wheel 10 and is opposite end secured to the casing for returning the count wheel to its normal position at the proper times.

The peripheries of the count and tally wheels are provided with corresponding numerals and graduations preferably indicating penny, five cent and ten cent marks, each wheel being graduated from the zero mark up to \$20.00. A clutch means is provided for the two wheels whereby one may be engaged with the other so that both wheels may be rotated in unison, and consists of circumferential clutch teeth 20 provided upon the adjacent faces of the wheels. Normally, the two wheels are spaced apart and when it is desired to rotate the two wheels in unison inward pressure is exerted upon the knob 17 of the stem which causes the count wheel 11 to move inwardly on the shaft 12 until its clutch teeth 20 engage with those of the coacting wheel. The knob is then turned

and thereby causes unitary rotation of the two wheels 10 and 11. The tally wheel 10 is retained in any position by pawl and ratchet means, a plurality of peripheral 5 ratchet teeth 21 being provided upon the tally wheel and adapted to cooperate with a spring pressed pawl 22 mounted upon the front of the casing 6. This pawl is urged into engagement with the ratchet teeth 21 10 by a flat spring 23 which is secured to the forward end of the casing and exerts inward force upon the working end of the pawl. The portion of the pawl disposed upon the opposite side of the pivot depends therefrom 15 and is engaged by a push pin 24 slidably mounted through the front of the casing and having a button or knob secured to the exposed end thereof. An abutment 25 is secured to the push pin and is disposed with- 20 in the casing to limit downward movement of the push pin caused by the spring 23 urging the pawl into engagement with its ratchet teeth.

From the foregoing description, it will be 25 seen that when it is desired to add several items with the device, the two wheels are positioned so that both register zero. For the purpose of clearness, it will be assumed that the purchaser has purchased two articles costing 20¢ and 30¢. The clerk exerts an inward pressure upon the knob 17 to cause the count wheel 11 to move so that its clutch teeth 20 engage the corresponding teeth of the tally wheel 10. During this operation, it is to be borne in mind that the coil spring 18 is tensioned or stretched. The knob 17 is then rotated to cause both wheels to rotate in unison until they register 20¢ directly beneath the pointers 9. Pressure 30 upon the knob 17 is then released and the coiled spring 18 draws the count wheel 11 away from its coacting wheel and returns the same to its normal position to register zero. Then to register the second purchase 35 amounting to 30¢ pressure is again applied to the knob, after which the two wheels are rotated in unison until the count wheel 11 registers 30¢ under the pointer 9 thereby causing the tally wheel to register 50¢ beneath the pointer. When the wheels are 40 rotated the first time, the spring pressed pawl 22 engages the ratchet teeth 21 and retains the tally wheel in its first position. After the count wheel has been actuated 45 to register the second purchase, the tally wheel is retained stationary by the pawl 22, while the count wheel is returned by the spring 18 to its normal position to register zero. 50 Assuming that the purchaser gives the clerk a \$1.00 bill for payment of the purchases, in order for the clerk to determine the amount of change to which the purchaser is entitled, he again forces the count 55 wheel into engagement with the tally wheel and turns the knob 17 to cause both wheels to rotate in unison until the tally wheel is rotated sufficiently to bring the \$1.00 mark thereof beneath the pointer 9. Then by glancing at the count wheel, the mark of 70 50¢ on the count wheel will be disposed beneath the pointer 9 and will indicate the amount of change to which the purchaser is entitled. After the clerk has completed his calculation, he then presses upon the 75 push pin 24 to release the pawl 22 from engagement with the ratchet teeth 21 which will permit return movement of the tally wheel, the count wheel having been returned by the spring 18 to its normal position. 80

The foregoing description and the drawing has reference to the preferred or approved form of my invention. It is to be understood however that such changes in construction and arrangement of parts, materials, dimensions, etc., may be made as prove expedient and fall within the scope of the appended claims.

Having thus fully described my invention what I claim as new and desire to secure by 90 Letters Patent is:—

1. A calculator comprising spring controlled rotatable count and tally wheels, clutch means between the wheels whereby they may be rotated in unison, means for 95 releasably retaining the tally wheels in a set position, and means for causing disengagement of the count wheel and independent return movement thereof.
2. A calculator comprising a casing having a sight opening therein, count and tally wheels rotatably mounted in the casing whereby their peripheries are visible through said sight opening, clutch means between the wheels whereby they may rotate 100 in unison, said wheels also being independently rotatable, springs associated with the wheels for causing their return movement, the spring associated with the count wheel being adapted to move the same laterally 105 of the tally wheel to disengage said clutch means whereby the count wheel may return to its normal position, ratchet teeth provided on the periphery of the tally wheel, and means slidably mounted through the 110 casing for association with said ratchet teeth for releasably retaining the tally wheel in fixed relation to the casing.
3. A calculator comprising a casing having a sight opening therein, a shaft extending transversely of the casing, journaled at one end within said casing, a tubular stem mounted in the side of said casing, and adapted to receive the other end of said 115 transversely extending shaft, a tally wheel 120 keyed to said shaft, a count wheel mounted on said shaft and connected to said tubular stem, spring means carried by said shaft and connected to said tally wheel to hold the same in a normal position, a second 125

spring mounted on said tubular stem, the convolutions thereof encircling said stem, one end of said spring being connected to said count wheel and the other end thereof fixed to said casing, clutch means between the wheels whereby they may rotate in unison, said wheels also being independently rotatable, ratchet teeth provided on the periphery of the tally wheel, and means 10 slidably mounted through the casing for as-

sociation with said ratchet teeth for releasably retaining the tally wheel in fixed relation to the casing.

In testimony whereof I affix my signature in presence of two witnesses.

WILFRED H. BUTCHER.
